DESIGN FOR A PLIANT PIPE COUPLING OR SIMILAR ARTICLE

Ivan Ročić, New York, N. Y.

Application March 7, 1942, Serial No. 106,116

Term of patent 3½ years

To all whom it may concern:

Be it known that I, Ivan Ročić, a citizen of Croatia, Yugoslavia, and a resident of the city of New York, county of New York, and State of New York, have invented a new, original, and ornamental Design for a Pliant Pipe Coupling or Similar Article, of which the following is a specification, reference being had to the accompanying drawing, forming part thereof.

Fig. 1 is a top plan view of a pliant pipe cou-

pling or similar article showing my new design, the bottom side being substantially the same;

Fig. 2 is a longitudinal sectional view thereof on the line 2—2, Fig. 1; and

Fig. 3 is a transverse sectional view on the line 3—3 of Fig. 1.

I claim:

The ornamental design for a pliant pipe coupling or similar article, as shown and described.

IVAN ROČIĆ.
